Mass., a corporation of Massachusetts

Original application December 27, 1937, Serial No.
181,776. Divided and this application May 19,
1939, Serial No. 274,608

3 Claims. (Cl. 139—37)

This invention relates to the production of tufted woven fabric and particularly to the cutting of the floating threads on the fabric to permit their formation into tufts or the like.

5 This application is a division of our co-pending application Serial No. 181,776, filed December 27, 1937.

In the production of a tufted woven fabric, threads of a character intended to form the tufts 10 are woven into the fabric with either the warp or the filling threads and are floated for a considerable distance on the surface of the fabric. The floating threads are then cut and given the proper finish to produce the desired tufted effect.

15 Prior to our invention, the operation of cutting the floating threads has been separate from the weaving process and difficult and expensive to perform because of the difficulty of severing the floating threads with the accuracy required.

20 An object of the present invention is to sever the warp floating threads as a part of the weaving operation.

A further object of the invention is the provision of means associated with the pattern 25 mechanism of the loom which operates automatically to sever the warp floating threads after they have been incorporated in the fabric and before the fabric is wound onto the take-up roll.

The cutting of the floating warp threads 30 is accomplished by a series of knives which are periodically reciprocated to move under the floating threads to sever them, the movement of the knife being effected under the control of the pattern chain or the equivalent. Such construction comprises a further object of the invention.

A still further object of the invention is generally to improve upon the severing of the tufted woven fabrics and mechanism for severing the floating threads.

40 Fig. 1 is a plan view, partly broken away, of a loom wherein the floating threads are woven in the fabric with the warp thread.

Fig. 2 is a front end detail view of the loom shown in Fig. 1.

45 Fig. 3 is a front elevation of a knife for severing the warp threads.

Fig. 4 is a view in side elevation of the knife shown in Figs. 2 and 3 and illustrating the manner in which the knife passes under and in contact with the floating threads.

In the illustrated embodiment of the invention, the floating threads are woven in the fabric with the warp threads, the floating threads being fed in with certain of the warp threads.

55 That is to say, a floating thread is disposed be-

side a regular warp thread so that the floating thread does not displace any warp thread. With this arrangement, the fabric shows an unbroken warp under the floating sections of the thread. The floating threads are controlled by separate harnesses 10 and in this instance a single shuttle loom is all that is necessary. It is evident, however, that multiple shuttle looms may be employed where necessary to produce a desired pattern or character of woven fabric. Multiple 10 shuttles, however, are not required to produce the tufted fabric. The arrangement of the floating sections can be anything desired; we have herein illustrated a simple design where the floating sections are arranged in rows and sections in 15 one row are staggered with respect to the sections in the next row.

As stated above, any type of loom may be used for the purpose. Preferably, the loom is provided with a plurality of harnesses 12 operated by the 20 usual jack levers 14 which are reciprocated by a head mechanism 16 under the control of the pattern chain 18. The loom is of the single shuttle type having a shuttle 20 for carrying the filling.

The woven fabric passes over the breast beam 25 22 around and between take up rolls (not shown) and is wound upon a winding shaft in the usual manner.

The cutting mechanism for the floating sections comprises a pair of parallel bars 24 and 26 30 disposed above the horizontal pass of the woven fabric on the breast beam 22. Each bar carries a plurality of cutting elements. Each cutting element comprises a feeler rod 28 and a vertical part or shank 30. The horizontal part rides 35 upon or close to the exposed face of the fabric and has a tapered end face 32 terminated in an edge 34 which can pass under the floating sections 36. A thin knife blade 38 is fastened to the feeler rod and has an inclined cutting edge 40 40 merging into the inclined face 32 of the feeler rod. Since the floating threads lie parallel with the direction of movement of the fabric, the cutter mechanism is adapted to be reciprocated at right angles to the line of fabric movement to 45 sever the floating threads. Thus, the horizontal section of the feeler rod is moved under the floating threads to raise them into loop form and carry them onto the knife 38 where they are severed.

The vertical or shank part 30 of the feeler rod is secured in a vertically and angularly adjustable manner by a set screw 42 in a chordal passage of a supporting collar 44 which is angularly adjustable and axially movable on one or the 55

other of the bars 24, 26 and is clamped in any adjusted position on the bar by a set screw 46. The bars are provided with as many cutter elements as there are floating sections to the fabric.

5 The ends of the bars are secured to brackets 48 which are secured to end frames 50 and 52. Said brackets are adjustable toward and away from each other on said frames to adjust the spacing between said bars in accordance with 10 different dispositions of the floating threads and also to adjust accurately the line of severance of the floating sections. The end frames have rigidly fixed thereto pairs of outstanding guide rods 54 which are reciprocatory in stationary bearings 56 and serve to guide the cutter elements for reciprocating movement.

15 The cutter elements are reciprocated in timed relation to the web movement by means of a bell crank lever 58 pivoted at 60 to the frame 20 and having one end connected to a link 62 with the end frame 50. The other arm of the bell crank lever 58 is connected through a safety spring 64 with a flexible strap or cable 66 which passes around sheaves 68 and 70 and is connected to the jack lever 72 the reciprocation of which is under the control of the pattern chain 18.

25 The pattern chain is provided with a pair of projecting studs 74 and 76, of which the stud 74 effects the reciprocation of the jack lever 72 in a direction to sever the floating strands or threads and the stud 76 acts to hold the cutting elements for a short time in their forward cutting position to more perfectly execute the complete cutting of the floating strands. The jack lever 72 returns automatically to its initial position when 30 free from control by the studs 74, 76. A tensile spring 78 connected with the end frame 52 and with a stationary part of the loom serves to effect the retraction of the cutting elements with the 35 mechanism above described.

40 The floating sections may be cut and formed into tufts very accurately and with little waste and during the weaving of the fabric and without adding appreciably to the cost of operation of the loom. The apparatus is simple and can be applied to almost any loom at small expense.

45 We claim:

1. In a loom for weaving tufted fabric, means for weaving selected warp threads to form floating warp sections on the face of the fabric, and mechanism for severing the floating warp sections including a plurality of supporting members 5 disposed transversely of the face of the fabric and adjustable longitudinally of the fabric relatively to each other, cutter elements adjustably secured to said supporting members and reciprocable transversely of the fabric to cut the floating warp 10 sections, and means for reciprocating the supporting members.

2. In a loom for weaving tufted fabric, means for weaving selected warp threads to form floating warp sections on the face of the fabric, and 15 mechanism for severing the floating warp sections including a plurality of bars disposed transversely of the face of the fabric, said bars being adjustable relatively to each other longitudinally of the fabric to space the bars in accordance with 20 the spacing of floating warp sections longitudinally of the fabric, cutter elements adjustably secured to said bars and reciprocable transversely of the fabric to cut the floating warp sections, and pattern controlled mechanism for reciprocating the bars.

3. In a loom for weaving tufted fabric, means for weaving selected warp threads to form floating warp sections on the face of the fabric, and mechanism for severing the floating warp sections including a plurality of bars disposed transversely of the face of the fabric, supporting means for said bars adjustable relatively to each other longitudinally of the fabric to space the bars in accordance with the spacing of the floating warp 30 sections longitudinally of the fabric, cutter elements adjustably secured to said bars and reciprocable transversely of the fabric to cut the floating warp sections, said cutter elements being secured to said bars in spaced relation in accordance with the transverse spacing of said floating warp sections, and pattern controlled mechanism for reciprocating the bars.
